UNITED STATES PATENT OFFICE.

HOWARD K. KING, OF PHILADELPHIA, PENNSYLVANIA, ASSIGNOR TO CHAMBERS BROTHERS COMPANY, A CORPORATION OF PENNSYLVANIA.

SLIP-SHEETING MACHINE.

1,180,652.

Specification of Letters Patent. Patented Apr. 25, 1916.

Application filed January 22, 1913. Serial No. 743,428.

To all whom it may concern:

Be it known that I, HOWARD K. KING, a citizen of the United States, residing at Philadelphia, in the county of Philadelphia, 5 State of Pennsylvania, have invented a new and useful Slip-Sheeting Machine, of which the following is a specification.

My invention relates to improvements in slip sheeting machines, and is an improvement or modification of the means shown in my Patent No. 1,094,908, dated Apr. 28, 1914. In that case advantage was taken of the different thicknesses of the printed sheets and the slip sheets, in operating a caliper 15 device which controlled pneumatically operated devices.

The present invention takes advantage of the difference in width or length of the slip sheets and the printed sheets, whereby 20 the shorter or narrower sheets escape a detector, and the longer or wider sheets encounter the same, as the case may be.

Referring to the drawings, which illustrate merely by way of example, suitable 25 means for effecting my invention, Figure 1 is a plan view. Fig. 2 is a fragmentary section on line 2—2 of Fig. 1. Fig. 3 is an end elevation of the switch and actuating mechanism on an enlarged scale. Fig. 4 is 30 a fragmentary view, part elevation and part section of some of the parts shown in Fig. 3 on a reduced scale. Fig. 5 is a fragmentary view in elevation of the latch and actuating means therefor. Fig. 6 is an end elevation of the valve tripping means. Fig. 7 is a section on line 7—7 of Fig. 6. Fig. 8 is a view similar to Fig. 7, with the exception that the cam and cam shaft are omitted and the valve trip is in a different position. Fig. 9 is a fragmentary plan view of the 35 trip lever and the slotted plate. Fig. 10 is a fragmentary plan view showing a switch element and associated mechanism. Fig. 11 is a perspective view of a switch element and the co-operating roller. Fig. 12 is a vertical section on line 12—12 of Fig. 10, on an enlarged scale. Fig. 13 is a vertical section on line 13—13 of Fig. 12. Fig. 14 is a similar view to Fig. 12, the parts in a different 40 position. Fig. 15 is a horizontal section on line 15—15 of Fig. 13. Fig. 16 is a detail of the bolt.

Similar numerals refer to similar parts throughout the several views.

Referring to Fig. 6 on the bracket 81 on

the stationary framework is pivoted at 82 the lever 17 actuated at its free end by the cam 18 engaging with roller 19 and the lever is controlled by the compression spring 20. On the same axis 82 is pivotally mounted 60 the lever 21 adjustably secured to lever 17 by means of the set-screws 22, which operate through lugs 23 on lever 21 embracing the short end of lever 17. On the free end of lever 21 is mounted the chambered body 24. 65 This valve chamber is provided with the cylinder 25 in which operates the valve piston 26 between conductors 27 and 28, 27 being connected with the source of air pressure and 28 being connected with a pneumatic diaphragm. 28 is also adapted to be separated from and connected with the exhaust port 29, by said piston. The valve piston 26 is normally controlled by the spring 30. The trip lever 31 is pivoted at 32 70 between the lugs 33 projecting downwardly from the chambered body 24. One end of this lever 31 is adapted normally to rest against the lug or projection 34, and the valve piston 26 is adapted to rest upon the 75 trip lever between the point of its pivot support and the other or free end of said lever. The guide plate 35 upon which the sheet 36 is adapted to travel, see Figs. 7, 8 and 9, is provided with the slot 37 adapted to register 80 with the outer end 38 of lever 31.

Operation: The operation of this device is as follows: The cam 18 is caused to rotate in certain relation with the delivery of sheets along the guide plate 35. The rotation of the cam 18 causes the oscillation of the lever 17, and consequently the lever 21, with a short dwell in one position and a long dwell in the other position, as the lever 21 is oscillated, or moved upwardly and downwardly. It will be understood that the trip lever 31, supports, on one side of its pivotal axis, the valve piston 26. The end of said trip lever on the other side of its pivotal axis normally rests against the lug 34. So long 90 as the trip lever 31 meets with no obstruction in the downward movement of the chambered body 24, the parts all remain in the same relative positions as shown in Fig. 7. It will be noted that in the upward and 95 downward movement of the chambered body 24, the trip lever 31 passes below the level of the guide plate 35, and, when there is no obstruction on said guide plate, the lever passes into and out of the slot 37, without 100 105 110

in any way affecting the movement of the several parts. When however, a sheet, such as 36, is of sufficient length or width to extend over the slot 37 as indicated by the dotted line 36', in Fig. 9, and also as indicated in Fig. 8, the trip lever 31 moving downwardly with the chambered body 24, will encounter the sheet in said downward movement and will be held stationary during the 10 balance of the downward movement of the chambered body 24. This causes the relative upward movement of the piston rod 26, thereby opening communication between the source of air pressure supply, and to the 15 pneumatic diaphragm. Upon the next upward movement of the chambered body 24, the trip lever, and consequently the valve piston assume normal conditions interrupting communication between air pressure and 20 diaphragm, and opening communication between diaphragm and exhaust, so that the diaphragm may assume normal conditions as hereinafter to be described.

As above indicated, the conductor 28 leads 25 from the valve chamber 24 to the diaphragm head 39. Within the diaphragm head 39 is secured the diaphragm 40, plate 41 secured thereto and piston rod 42 secured to the plate. Piston rod 42 is pivotally secured at 43 to lever 44. Lever 44 is secured to the shaft 45 which has operative relationship with the shaft 46 upon which are mounted the switch elements 47. The outer end of lever 44 is controlled by the spring 30 48. In Fig. 4, the diaphragm and diaphragm plate are shown in the depressed position, that is, with air pressure in the diaphragm head 39 consequently the piston rod 42 is shown in the depressed position and 35 the switch elements in the position with the points 49 out of the channels 50 of the roller 51. When pressure is relieved from diaphragm chamber 39 and the latch 52 is disconnected from the end 53 of lever 44 the 40 spring 48 tends to return the lever into the position shown in Fig. 3, in which the ends 45 49 of the switch elements rest in the channels of roller 51.

As already explained, in said Patent No. 50 1,094,908, the switching elements 47 in one position serve to deflect the sheets, as they pass between drop and feed rollers 51' and 51 respectively, to one pile and in another position permit the sheets to be delivered 55 to another pile. For example, in arrangement shown in Fig. 2, the switching elements are in such position that the points 49 are withdrawn from the channels of the roller 51 so that the sheet is delivered between roller 51 and switching elements 47 to 60 pile 54 by means of suitable nippers 55 on endless chains 56 already described in my said patent. Whereas when the switching elements are shifted into position shown in 65 Fig. 3 with points 49 resting in the channel

50 the sheets will be carried over the top of the switching elements 47 along guides 57 to be engaged by the grippers 58 on the endless chain 59 and be delivered to the pile 60. The latch member 52 is pivotally secured at 61 and is normally controlled by the spring 62. As above indicated, it is adapted to engage the outer end 53 of lever 44. The outer or latching end 53 of said lever is inclined on its lower side and is adapted to 70 wipe the arc shaped surface 63 which lies in an arc having a center at 45 when in engagement with the end 53 so that when the end of lever 44 is moved downwardly to its lowest position it passes the extension of the arc surface and at the end of which the latch 52 is forced above the point 53 by its spring 62 into engagement as shown in Fig. 4. The projection 65 is provided for preventing the lever 52 from being actuated past the 80 point 53 of lever 44. The latch lever 52 is also provided with a bifurcated wing or projections 65' which are adapted to be engaged by the bosses 66 on the arms 67 so that as the arms rotate, the bosses, in the 85 proper periods of the machine's operation, disengage the latch from the arm 44, to permit the same to return to normal or spring actuated position.

The purpose of this latching mechanism 95 is to maintain the lever 44 in the depressed position, as shown in Fig. 4, until the sheet has cleared the point 49, as it passes around roller 51. The arms 67, carrying the bosses 66, have suitable relative rotation, with respect to the other operations of the machine, 100 in order to release the latch, after the sheet has cleared, as above pointed out.

Operative relationship between shaft 45 and shaft 46 is secured by means of universal gear mechanism comprising pinions 69, 70, 71 and 72, mounted in the ring or housing 73 as shown in Fig. 13. Pinions 69 and 71 are keyed to shafts 45 and 46 respectively, while pinions 70 and 72 are 105 mounted on studs connected with the ring or housing 73. In the housing or ring 73 is also mounted the bolt 76, having the operating pin or handle 77. The bracket 79 is connected with the stationary framework 110 of the machine and is recessed to receive the bolts 76 as clearly shown in Figs. 12 and 13. Secured to pinion 72 is the collar 74, similarly recessed at 75 to receive the other end of the bolt 76. The spring 78, 115 see Fig. 15, is provided to coöperate with handle 77 to maintain the bolt in either position, that is, in the position shown in Figs. 12 and 13, where it is engaged with the bracket 79, or in the elevated position 120 engaging with the collar 74.

The operation is as follows: When the bolt is in engagement with the bracket 79 the ring or housing 73 is prevented from turning, whereupon the pinions rotate and 130

the driving shaft 45 transmits motion through the pinions 70 and 72 to pinion 71 thus rocking the shaft 46 in directions opposite to the movements of shaft 45. When, on the other hand, bolt 76 engages in recess 75 of collar 74, the pinions are all locked with the housing, and hence the two shafts are practically locked together and rotate together. One of the advantages of such an arrangement is this, that where for any reason it is desired to shift the relative directions of the sheets, for example, if with the two shafts locked together the larger sheets were going over switch elements 47 and the smaller sheets were going around the roller 51 and it was desired to change this order it would be necessary simply to bolt the housing to the bracket 79 and the distribution would be reversed.

20 By the use of the phrase "different surface areas" in the claims I mean differences either in length or width of the sheets operated upon.

What I claim is:—

25 1. In combination with sheet supporting and positioning means, means for automatically separating sheets of different surface areas, having a preliminary common path of travel, comprising a sheet switching device adapted to be moved into and out of said path of travel, pneumatically operated means for controlling the same, including a pneumatic valve and a valve tripping device adapted to encounter sheets only of predetermined surface area.

2. In combination with sheet supporting and positioning means, means for automatically separating sheets of different surface areas, having a preliminary common path of travel, comprising a sheet switching device adapted to be moved into and out of said path of travel and coöperating guides, pneumatically operated means for controlling the same, including a pneumatic valve and a valve tripping device adapted to encounter sheets only of predetermined surface area.

3. In combination with sheet supporting and positioning means, means for automatically separating sheets of different surface areas, having a preliminary common path of travel, comprising a sheet switching device adapted to be moved into and out of said path of travel, pneumatically operated means for controlling the same, including a pneumatic valve and an oscillating valve tripping device adapted to encounter sheets only of predetermined surface area.

4. Means for feeding and automatically delivering sheets of different dimensions first along a common path of travel and then to different points respectively comprising a switching device adapted to be moved into and out of said common path

of travel, actuating means for causing said movement, a control for said actuating means comprising a tripping device positioned and operated to encounter sheets of one dimension only and means, also included in said actuating means, for arbitrarily reversing the direction of said actuation.

5. Means for feeding and automatically distributing sheets to different points or piles, controlled by the respective surface dimensions of each sheet, and manually operative means for arbitrarily changing the order of such alternative distribution.

6. In combination with sheet supporting and positioning means, means for automatically separating sheets of different surface areas, having a preliminary common path of travel, comprising a sheet switching device adapted to be moved into and out of said path of travel, pneumatically operated means for controlling the same, including an oscillating valve mechanism and a valve tripping device carried thereby adapted to encounter sheets only of predetermined surface area.

7. In combination with sheet supporting and positioning means, means for automatically separating sheets of different surface areas, having a preliminary common path of travel, comprising a sheet switching device adapted to be moved into and out of said path of travel, pneumatically operated means for controlling the same, including a chambered body, a valve piston adapted to reciprocate therein, a piston actuating trip lever, a pivot support therefor and means for oscillating said support to bring the lever into engagement with sheets of predetermined surface area.

8. In combination with sheet supporting and positioning means, means for automatically separating sheets of different surface areas, having a preliminary common path of travel, comprising a sheet switching device adapted to be moved into and out of said path of travel, pneumatically operated means for controlling the same, including a chambered body, a valve piston adapted to reciprocate therein, a piston actuating trip lever pivotally connected with the chambered body and means for oscillating said support to bring the lever into engagement with sheets of predetermined surface area.

9. Means for feeding and automatically delivering sheets of different dimensions first along a common path of travel and then to different points respectively comprising a switching device adapted to be moved into and out of said common path of travel, actuating means for causing said movement, a control for said actuating means comprising a tripping device positioned and operated to encounter sheets of one dimension only and manually operative means, also included in said actuating

means, for arbitrarily reversing the direction of said actuation.

10. Means for feeding and automatically delivering sheets of different dimensions first along a common path of travel and then to different points respectively comprising a switching device adapted to be moved into and out of said common path of travel, actuating means for causing said movement, a control for said actuating means comprising a tripping device positioned and operated to encounter sheets of one dimension only and means, also included in said actuating means, for arbitrarily reversing the direction of said actuation while the machine is operating.

11. A control for a pneumatically operated device comprising a valve casing, a valve piston operating therein, a valve trip controlling the movement of the piston, means for moving the valve trip and the piston together across the path of travel of a sheet of required dimension, sheet-switching means and means controlled by the valve trip for operating the switch.

12. In combination with means for supporting and positioning sheets, a control for pneumatically operated devices comprising a valve casing, means for reciprocating the same, a valve piston, an arm pivoted to the valve casing normally supporting the piston in one position, said arm adapted to encounter sheets of required dimension during the reciprocating movement of the valve casing to cause the actuation of the piston.

13. A reciprocating valve casing, having a plurality of ports, a movable valve element co-operating with said ports, a member pivoted to the valve casing and supporting the movable valve element, and a sheet guide and support having a slot for receiving a pivoted member during the passage of a sheet of required dimension along the support, the position of the valve element relatively to the valve casing being controlled by the position of the pivoted member relatively to the slot.

14. In a sheet feeding machine the combination of a sheet switching element, an actuating lever therefor, pneumatic means

for moving the actuating lever, latching means for securing the lever in its actuated position and means moving relatively with the operative parts of the machine for releasing the latch.

15. In a sheet feeding machine the combination of a sheet switching element, a spring controlled actuating lever therefor, pneumatic means for moving the actuating lever, latching means for securing the lever in its actuated position and means moving relatively with the operative parts of the machine for releasing the latch.

16. In a sheet feeding machine the combination of a sheet switching element, an actuating lever therefor, pneumatic means controlled by sheets of required dimension for moving the actuating lever, latching means for securing the lever in its actuated position and means moving relatively with the operative parts of the machine for releasing the latch.

17. In a sheet feeding machine, the combination of a sheet switching element, a spring controlled actuating lever therefor, pneumatic means controlled by sheets of required dimension for moving the actuating lever, latching means for securing the lever in its actuated position and means moving relatively with the operative parts of the machine for releasing the latch.

18. In combination with parallel sets of drop and feed rollers spaced apart, one of said sets adapted to feed sheets to the other set, sheet supporting and positioning means, means for automatically separating sheets of different surface areas, having a preliminary common path of travel, comprising a sheet switching device adapted to be moved into and out of said path of travel, pneumatically operated means for controlling the same, including a pneumatic valve and a valve tripping device adapted to encounter sheets only of predetermined surface area passing from one set of rollers to the other.
